THREE-WAY CLAMPING FIXTURE

Alfred V. McFerron, Rocky River, and Harold D. Myers, Cleveland Heights, Ohio, assignors to McFerron-Myers Products Company, Rocky River, Ohio, a corporation of Ohio

Application February 25, 1948, Serial No. 10,736

1 Claim. (Cl. 113—99)

1

This invention relates to improvements in a so-called three-way clamping fixture for supporting two or more elongated parts while they are being joined together as for instance by welding.

An object of the present invention is to provide simple but convenient means of novel and improved character for holding two or more bars, rods, tubes or other similar elongated articles for joining together at a common point, said means further comprising various frames and brackets which provide the desired support for the work pieces.

A further object of the invention is to provide novel and improved clamping fixture means of the character indicated in the last preceding paragraph having at least two complementary parts which are identical with each other, so as to be perfectly interchangeable in multiple clamping set-ups.

A further object of the invention is to provide a three-way clamping fixture of the character described, comprising at least two clamping portions adjustably movable with respect to each other, and having respectively adjacent portions provided with convenient indicia for indicating the relative positions of their clamping faces, as will more clearly appear from the accompanying specification and drawings, and the essential features will be set forth in the appended claim.

In the drawings:

Fig. 1 is a perspective view of a three-way clamping fixture embodying our invention;

Figs. 2 and 3 are sectional views taken respectively on the lines 2—2 and 3—3 of Fig. 1;

Fig. 4 is a perspective view, similar to Fig. 1, but showing a modified form of the present invention.

Fig. 5 is a view, considerably reduced in size as compared with the other drawings, showing a pair of clamping fixtures adapted for use with a spacer bar.

Figs. 1 to 3 show a generally U-shaped frame 10 the legs of which terminate in a pair of blocks having face portions 11a and 12a provided with work-supporting jaws 11b and 12b respectively. A tongue or handle 13 extends rearwardly from the mid portion of the frame 10 so as to provide means for either holding the clamping fixture manually, or gripping it in a vise, or otherwise. The tongue 13, the frame 10, and the clamping blocks 11 and 12 all lie generally in a common plane.

Jaws 11 and 12 have threaded perforations 11c,

2

12c for the purpose of receiving attaching means for a C-clamp 14 or similar attaching device, the fixed end of a C-clamp being shown in Fig. 1, and being retained on block 12 by removable attaching means 15, in the present instance consisting of a threaded stud.

The movable jaw of the clamp is adapted to be moved against a work piece resting in the groove 12b of block 12.

Means is provided for positioning a third clamping block 16 in position to cooperate with blocks 11 and 12, and in the position shown in Fig. 1 the working face 16a of block 16 is in the plane of faces 11a and 12a of blocks 11 and 12. Block 16 and a similar block 17 are supported by an arcuate frame portion 18, corresponding generally in structure and function to frame 10 previously described, except that frame 18 is of such length that blocks 16 and 17 are at right angles to each other.

Block 17 is longitudinally slidable on tongue 13 of frame 10, and is held in place in various adjusted positions relative to tongue 13 by a bolt 19 (Fig. 2) which passes through a slot 20 in tongue 13, and seats in a threaded aperture 17c in the block 17. This is the same threaded aperture which is adapted to receive the attaching stud for the fixed end of a C-clamp when the block happens to be in clamp-holding position. Slot 20 may be a single long slot, or a succession of shorter slots.

Novel means is provided for strengthening the frame 10, and for guiding the block 17 (or block 16 if in the position now occupied by 17 in Fig. 1) during sliding movement thereof. Upstanding ribs 23 extend around the outer edges of the frame 10, and backwardly at 23a along the longitudinal edge faces of tongue 13. The rib portions 23a slidably engage the vertical side faces of block 17 to guide it during its adjustable movement. Other ribs 24 are provided around the inner edge of the U-shaped frame 10 for strengthening purposes. These ribs may be cut away, as indicated at 24a so as to permit sliding movement of block 17 in case the forward end of this member should extend into the recess of the U-shaped frame. Similar strengthening ribs may be provided along the arcuate edges of frame 18.

For convenience in duplicating previous adjustments, clamping fixtures 10 and 18 can be provided with means for re-establishing any desired positional relationship between face 16a of block 16, and the co-planar faces 11a and 12a.

55 As shown in Fig. 1 this means consists of an

indicia scale 25 fixed on the side of block 17, and a pointer 26 or other reference means fixed on rib 23a. As will be readily understood, the indicia scale and pointer may be arranged to directly read the linear divergence between the plane of face 16a and the common plane of faces 11a and 12a. In the position shown in Fig. 1 the pointer would be at the zero position on the scale since the above mentioned planes coincide in the Fig. 1 position.

The ninety degree fixture 18 is also provided with a tongue 27 the structure and function of which are similar to those already described for fixture 10. Briefly, tongue 27 can be used for holding fixture 18 in the hand, or grasping it in a vise or otherwise, or even as a runway on which the base blocks of additional clamping structures may be attached. A complex clamping unit may be built up in this way, to hold a plurality of rods, tubes, or other articles for welding, or other operation.

In the assembly shown in Fig. 4, two ninety degree units 28 and 29 are shown mutually attached in position to hold, for example, three rods (not shown) which meet at a common point constituting the corner of a hollow polyhedral figure such as a cube. It may be noted that clamping structures 28 and 29 are identical and are therefore exactly interchangeable in any working position. This is a distinct advantage in a shop where a plurality of related operations are going on, and a workman can select one or more clamping parts from a common pile without wasting too much time in seeking one of specific shape.

Fig. 5 shows a pair of clamping units 30 and 31 adjustably fixed on the ends of a spacer bar 32 which can be of any suitable length depending on the requirements of the job.

We have referred to the frame 10 as being of U-shape. We do not desire to be limited specifically to the shape shown in the drawings, since the frame may have rectangular corners, or it might be of V-shape, but the term U-shape has been used for simplicity of description.

It should be clearly understood that all of these fixtures have blocks 11, 12, 16 and the blocks of units 28 and 29 of the same width, and the spaces between ribs 23a and similar ribs of the other

units are all of corresponding width to slidably receive any of these blocks. Therefore, any number of units of selected angular relationship (or of variable angular relationship as disclosed in Fig. 1 of our co-pending application, Serial No. 649,944, filed February 25, 1946, now abandoned) may be added together like building blocks, and spacer bars 32 may be inserted at any points needed.

It will be noted that any one of the clamping frames shown in Fig. 1 or Fig. 4 includes a pair of branching arms (10 and 18 in Fig. 1 and 28 or 29 in Fig. 4) having a rigid tongue (13 or 27 in Fig. 1, and similar tongues in Fig. 4) extending away from the junction of the arms to form what may be designated a Y-shape frame.

What we claim is:

A clamping fixture comprising a Y-shape rigid frame, the frame having a pair of branching arms and a tongue extending away from the junction of said arms, a block at the free end of each of said arms and rigid therewith, each said block being constructed and arranged to support work clamped to a face thereof, each said block having parallel sides on opposite sides of said face, parallel ribs on said tongue spaced apart a distance substantially equal to the distance between said parallel sides, the tongue being adapted to receive a block of a second similarly constructed clamping fixture between said ribs in slidably, locking relation thereto.
